UNITED STATES PATENT OFFICE.

MORRIS G. GOLDBERG, OF NEW YORK, N. Y., ASSIGNOR TO THE MONARCH TYPEWRITER COMPANY, OF SYRACUSE, NEW YORK, A CORPORATION OF NEW YORK.

TYPE-WRITING MACHINE.

1,009,299.

Specification of Letters Patent. Patented Nov. 21, 1911.

Application filed June 19, 1911. Serial No. 633,922.

To all whom it may concern:

Be it known that I, MORRIS G. GOLDBERG, a citizen of the United States, and resident of the borough of Manhattan, city of New York, in the county of New York and State of New York, have invented certain new and useful Improvements in Type-Writing Machines, of which the following is a specification.

10 My invention relates to typewriting machines and more particularly to indicating means to aid in properly centering a sheet with reference to the platen and to facilitate properly centering a heading on the paper.

15 The object of my invention, generally stated, is to provide simple and efficient means of the character specified.

To the above and other ends which will hereinafter appear, my invention consists 20 in the features of construction, combinations of devices and arrangements of parts to be hereinafter described and particularly pointed out in the appended claims.

In the accompanying drawings wherein 25 like reference characters indicate corresponding parts, Figure 1 is a fragmentary, front elevation, showing the upper portion of a Monarch machine embodying my invention, parts of the construction being omitted 30 for clearness of illustration. Fig. 2 is a transverse, sectional view of the same.

I have shown my invention embodied in the present instance in a Monarch machine in which the invention may be readily included without changing the structural features of the machine. It should be understood, however, that the invention is applicable to, and may be embodied in, various styles of typewriting machines.

40 The frame of the machine comprises corner posts 1 and a top plate 2. Guide rails 3 are fixed to the top plate of the machine in the usual manner and have their opposite faces grooved for the reception of anti-friction 45 balls or rollers 4 which are likewise received in oppositely grooved rails 5 of a guide bar 6, which constitutes the rear cross bar of the carriage. Forwardly projecting end bars 7 extend from the carriage and are 50 provided with bearings to receive a platen shaft 8, on which a rotative cylindrical platen 9 is mounted. The carriage is thus mounted for movement over the top plate of the machine from side to side thereof.

55 Type bars 10 are pivoted to strike upwardly

and rearwardly against the front face of the platen. The usual paper feed equipment may be embodied in the machine, although parts of the paper feed mechanism have been omitted and other parts have been only 60 diagrammatically illustrated. The paper table 11 is mounted on the carriage to direct the paper to the right between the platen and main feed rollers 12. Forward feed rollers 13 coöperate with the paper to feed 65 it upwardly to the printing line and margin feed rollers 14 of the usual construction may likewise be provided. The paper in its movement past the feed rollers 13 passes under a combined platen and carriage scale 70 15 with which a pointer 16 on a card guide 17 coöperates. The printing point represented at X in Fig. 1 is indicated by the usual printing point indicator carried by the card guide. A cross bar 18 is connected at 75 its ends to the end bars 7 of the carriage and is situated above the platen in a position where the paper a, as it passes upwardly and rearwardly from the printing line, may pass over said bar. An erasing plate 19 is carried by the bar 18 in the usual manner; the lower edge of the plate contacting with the platen and the upper edge thereof being arranged at the top of the bar. The erasing plate is thus maintained at an inclination, as 80 85 represented in Fig. 2, to provide an efficient erasing plate, and as the leading edge of the paper passes above the platen it is deflected over the supporting bar 18 so that the paper rests above and passes over the erasing plate 90 and bar.

The mechanism thus far described constitutes part of the usual equipment of the Monarch machine and further detailed description thereof is deemed unnecessary.

95 For the purposes of my present invention I provide indicating means arranged above the platen and coöoperative with the work sheet, or the side edges thereof, to properly center the work sheet with reference to the 100 platen. I prefer to arrange the indicating means on the erasing plate 19, and as shown in Fig. 1; the indicating means preferably comprises a divided scale, one portion or section of the scale being arranged to the right-hand of the center of the erasing plate and the other portion or section of the scale being arranged at the left-hand side of the center of the erasing plate. The scale is preferably provided with scale marks 20 spaced apart 110

at letter space distances and is also provided with numerical indices 21 which in the present instance progress in opposite directions on the two scale sections. Thus the left-hand scale section has the numerical indices "0," "10," "20" and "30" progressing toward the center of the erasing plate, which plate constitutes a support or carrier for the scale. Corresponding numerical indices are 5 provided at the opposite side of the center of the erasing plate and these numerical indices likewise progress from the outer end toward the center of the divided scale. Both sections of the scale are alike, except that the 10 numerical indices thereon progress in opposite directions and both sections of the scale are in the same plane and are in alinement longitudinally of the platen. Preferably the scale marks or indices 20 on the centering scale, which latter is designated as a 15 whole by the reference numeral 22, are in alinement with the indices on the platen and carriage scale.

In order to properly center a heading on 20 the sheet with the aid of my invention, the work sheet *a* is introduced into the machine in the usual manner and is properly centered with reference to the platen by bringing the side edges of the work sheet into 25 register with the corresponding indices at opposite ends of the centering scale 22, as shown in Fig. 1. With the sheet thus properly centered relatively to the platen, the operator will count the number of spaces in 30 the heading to be produced, including in the calculation the spaces between words and those occupied by punctuation. As an example, a centered heading has been shown in Fig. 1 on the work sheet. The heading 35 comprises the words "A centered heading." It will be seen that the spacing between the words and the letters in this heading occupies eighteen spaces. The operator will then place the carriage in position where the carriage scale will be equally divided. Thus in 40 the present instance the carriage scale indicates seventy-six letter space movements. The mark which indicates thirty-eight on the carriage scale is then brought into register with the pointer 16 to properly center the carriage with reference to the printing point. The operator may then move the carriage 45 backwardly or to the right one-half the number of spaces occupied by the heading. The heading in the present instance occupies 50 eighteen spaces. The operator will therefore move the carriage back nine spaces. In the Monarch machine this may be readily effected by the back spacing key. The writing 55 of the heading may then be proceeded with and it will be found to be properly centered on the sheet. If the heading should occupy an uneven number of spaces, say, for example, nineteen, then the operator will 60 move the carriage back one-half the number

of spaces plus one, which in the last example would be ten, and then write the heading, and it will be found to be exactly centered.

It will be observed that in accordance with my present invention the centering scale is 70 arranged at the delivery side of the platen and in a position where the paper, after its leading edge leaves the printing point or printing line, may pass over the scale to afford an easy centering of the work sheet 75 with reference to the centering scale by bringing the side edges of the work sheet into register with the indices on the scale. Moreover, it will be understood that the centering scale may, in accordance with my 80 present invention, be readily applied to the Monarch machine without modifying any of the structural features of that machine.

What I claim as new and desire to secure by Letters Patent, is:—

85

1. In a front strike typewriting machine, the combination of a rotative platen with a work sheet centering scale located at the delivery side of the platen and having corresponding indices at opposite ends thereof, 90 whereby a work sheet may be centered relatively to the platen.

2. In a front-strike typewriting machine, the combination of a rotative platen, with a work sheet centering scale located at the 95 delivery side of the platen and having numerical indices that progress in opposite directions, corresponding numerical indices being provided at opposite sides of the center of the scale, whereby a work sheet may 100 be centered relatively to the platen.

3. In a front-strike typewriting machine, the combination of a rotative platen, with a work sheet centering scale located at the delivery side of the platen, said scale being in 105 the nature of a divided scale formed of two sections arranged in alinement longitudinally of the platen and having numerical indices which progress in opposite directions, whereby a work sheet may be centered 110 relatively to the platen.

4. In a front-strike typewriting machine, the combination of a rotative platen, with an erasing plate at the delivery side of the platen and over which the paper passes after 115 the leading edge thereof leaves the printing line, and a work sheet centering scale carried by said erasing plate, said centering scale having corresponding numerical indices at opposite end portions thereof, the 120 numerical indices progressing in opposite directions, whereby a work sheet may be centered relatively to the platen.

5. In a front-strike typewriting machine, the combination of a rotative platen, a 125 printing instrumentality adapted to strike against the front face of the platen, an erasing plate at the delivery side of the platen and arranged above it and over which the work sheet passes after the leading edge 130

thereof passes the printing line, and a work sheet centering scale carried by said erasing plate on the upper face thereof and over which the work sheet passes, the scale having corresponding indices at opposite end portions thereof, whereby a work sheet may be centered relatively to the platen.

6. In a front-strike typewriting machine, the combination of a rotative platen, a printing instrumentality adapted to strike against the front face of the platen, an erasing plate at the delivery side of the platen and arranged above it and over which the work sheet passes after the leading edge thereof passes the printing line, and a work sheet centering scale carried by said erasing plate

on the upper face thereof and over which the work sheet passes, the scale having corresponding numerical indices at opposite end portions thereof, the numerical indices progressing in opposite directions, whereby a work sheet may be centered relatively to the platen. 20

Signed at the borough of Manhattan, city of New York, in the county of New York, 25 and State of New York, this 14 day of June, A. D. 1911.

MORRIS G. GOLDBERG.
